(57) **CLAIM**

The ornamental design for an electric heater as shown and described.

DESCRIPTION

FIG. 1 is a perspective view of a electric heater showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged detail view of area **9** circumscribed in FIG. 1;

FIG. 10 is an enlarged detail view of area **10** circumscribed in FIG. 1;

FIG. 11 is an enlarged detail view of area **11** circumscribed in FIG. 2; and,

FIG. 12 is an enlarged detail view of area **12** circumscribed in FIG. 2.

The evenly spaced broken lines depict portions of the electric heater and form no part of the claimed design. The long dash-short dash broken lines in FIGS. 1-2 and 9-12 denote the boundaries of the enlarged detail view and form no part of the claimed design.
